UNITED STATES PATENT OFFICE

RUSSELL S. CARTER, OF HEWLETT, NEW YORK

FOUNTAIN PEN

Application filed December 19, 1929. Serial No. 415,184.

Heretofore it has been proposed to collapse the ink sacks of fountain pens (as a preliminary to refilling) by air pressure developed in the barrels of the pens in various ways. For example, it has been proposed to build the barrel in two or more telescoping parts, so that by pumping one barrel part on another as it were, a slight super-atmospheric pressure can be produced inside the barrel to 10 collapse the sack. Again, I myself have heretofore proposed to give the pen cap a long sliding fit on the outside of the pen barrel so that (the barrel being perforated to admit air from the cap) the ink sack may be collapsed by sliding the cap over the barrel. The sacks being collapsed, these pens are re-filled ordinarily by releasing the air pressure, and thus permitting the sacks to re-expand by their own resiliency while the pen points 20 are submerged in ink. Universally the ink sacks have heretofore been cylindrical in shape in their normal or expanded condition.

The sack-collapsing force developed in the compressed-air type of pen is so small however, that it has been found difficult to so co-relate the sack wall to the pressure as to cause the ink to always fill all of the space available for it. I have found that this difficulty can be minimized by corrugating the 30 wall or walls of the ink sacks, or in any other way making the ratio of the area of the wall surface to the sack volume greater than the corresponding ratio in straight-sided or simple cylinders.

35 The accompanying drawings illustrate my present invention as applied to the compressed-air pen heretofore proposed by me; it will be understood however that my present invention is not limited to this particular 40 pen construction, but is applicable to all forms of compressed-air pens, i. e. pens in which the sacks are collapsed for refilling by air pressure.

In the drawings: Fig. 1 is for the most part 45 a sectional view of the pen, showing its ink sack in elevation. Fig. 2 is a cross-section of the ink sack of Fig. 1, about on the line II-II. Fig. 3, partly in section, shows the pen of Fig. 1 with the ink sack collapsed 50 preparatory to refilling. Fig. 4 is an eleva-

tion of the pen closed, the cap being in section. Fig. 5, partly in elevation and partly in section, illustrates another form of ink sack of my present invention.

As usual, the barrel 1 of the pen is provided with a finger portion 2 carrying the pen point 3, while the cap 6 is arranged to be fastened over the pen point (Fig. 4) by screw threads 7. The end 11 of the barrel is perforated at 13, while the side walls of 55 the cap is perforated at 14. The open end of the ink sack 5 fits tightly over the flange 4 of the finger portion 2, in the customary manner. In accordance with the present invention, the outer surface of this ink sack 60 5 is corrugated longitudinally (Figs. 1 and 2) and the inner surface of the wall of the sack corresponds to its outer surface; that is to say in the present instance, the inner surface of the side wall or walls of the sack is 65 corrugated in the same manner as the outer surface and the internal and external corrugations substantially fit into each other 70 (Fig. 2). The thickness of the wall of the sack may be about the same throughout the 75 whole sack. The sack 5 being self expanding, that is to say, when exposed to substantially equal pressures internally and externally, it tends to restore itself to the shape in which it is illustrated in Figs. 1 and 2, the 80 operation of refilling the pen may be as follows: The cap 6 being placed on the barrel in the position shown in Fig. 1, the perforation 14 is closed by the finger and then the cap 85 slid over the barrel to say the position of Fig. 3; the shoulder 15 stops the cap 6 before the perforation 14 is closed by the barrel lapsing it. Externally the barrel 1 is cylindrical from the shoulder 15 to the end 11 and internally the cap 6 is cylindrical from its 90 open end to the perforation 14; also the internal diameter of the cap 6 is but slightly greater than the external diameter of the barrel 1. Hence sliding cap 6 from the position of Fig. 1 to its position of Fig. 3, with the 95 perforation 14 held closed, forces air into the barrel 1 through the perforation 13 and the super-atmospheric pressure thus developed within the barrel serves to collapse the ink sack 5 as indicated in Fig. 3. By increasing 100

the ratio of the area of the wall surface of the sack to the sack volume, by the corrugations described, a greater area is effectively presented to this air pressure than were the sack 5 a simple straight-sided cylinder as heretofore, and hence the available air pressure is made more effective for collapsing the sack. The pen point 3 now being submerged in ink, the air pressure within the barrel is released by 10 opening port 14. This permits the ink sack 5 to restore itself to its expanded condition of Fig. 1, and in doing so suck up into itself a new charge of ink.

Instead of being corrugated longitudinally 15 the ink sack may be corrugated transversely both internally and externally, as illustrated in Fig. 5. It will be understood however that my invention is not limited to the particular forms of it herein illustrated and described, except as appears hereinafter in the 20 claims.

I claim:

1. A fountain pen of the compressed-air 25 type having an ink sack, characterized by the fact that the ratio of the area of the wall surface of the sack to the sack volume is greater than the ratio of wall surface to volume in a straight-sided cylindrical ink sack.

2. A fountain pen of the compressed-air 30 type having an ink sack, characterized by the fact that the ratio of the area of the outer surface of the wall of the sack to the volume of the hollow of the sack is greater than the corresponding ratio of a straight-sided cylindrical ink sack, and the inner surface of the 35 wall of the sack corresponds to its outer surface.

3. The combination with a fountain pen 40 provided with means through which a sack-collapsing air pressure can be developed within the pen barrel, of a corrugated ink sack.

4. The combination with a fountain pen 45 provided with means through which a sack-collapsing air pressure can be developed within the pen barrel, of an ink sack corrugated externally at its side walls and correspondingly corrugated internally.

5. The combination with a fountain pen 50 provided with means through which a sack-collapsing air pressure can be developed within the pen barrel, of an ink sack corrugated longitudinally externally and the inner surface of its corrugated walls substantially corresponding to the outer surface 55 thereof.

6. The combination with a fountain pen 60 provided with means through which a sack-collapsing air pressure can be developed within the pen barrel, of a self-expanding ink sack corrugated externally at its side walls and correspondingly corrugated internally.

7. In a fountain pen, the combination of 65 an ink sack, corrugated both internally and externally, a member surrounding the same, said member being open remote from the pen

point end of the pen, and a second member 70 slid able over the first-mentioned member to compress air within the first mentioned member and externally of the ink sack to collapse the latter.

In testimony whereof, I have signed this 75 specification.

RUSSELL S. CARTER.
